UNITED STATES PATENT OFFICE.

CLARENCE MAYER, OF CHICAGO, ILLINOIS, ASSIGNOR TO NATURES RIVAL COMPANY, OF CHICAGO, ILLINOIS, A CORPORATION OF ILLINOIS.

BRASSIÈRE.

1,168,732.

Specification of Letters Patent. Patented Jan. 18, 1916.

Application filed June 10, 1914. Serial No. 844,122.

To all whom it may concern:

Be it known that I, CLARENCE MAYER, a citizen of the United States, and a resident of Chicago, in the county of Cook and State 5 of Illinois, have invented certain new and useful Improvements in Brassières; and I do hereby declare that the following is a full, clear, and exact description thereof, reference being had to the accompanying 10 drawings, and to the characters of reference marked thereon, which form a part of this specification.

This invention relates to improvements in bust supporting and reducing brassières.

15 The invention relates more specifically to the construction of the front bust sections of such brassières, and the invention consists in the matters hereinafter set forth and more particularly pointed out in the appended 20 claims.

25 Among the objects of the invention is to provide an arrangement whereby the hollow or cup-shaped elastic bust sections may be made from elastic strips or webbing of commercial widths, so as to thereby avoid the use of special machinery or appliances for producing such bust sections.

30 A further object of the invention is to reduce the cost of the garment.

35 A still further object of the invention is to provide a novel method of joining or stitching together the elastic strips in such manner as to enhance the elasticity of the resultant bust sections.

40 A bust supporting and reducing section or brassière embodying my invention is made up of a plurality of elastic strips which are joined together at their marginal portions, preferably in overlapped relation, by stitches extending through the overlapped portions thereof, and are fashioned and assembled in such manner that in their assemblage they form a cup-shaped section of desired contour.

45 In accordance with my novel method of joining the strips when making up the bust section, the said strips are laid one upon the other in overlapping relation at their marginal portions in proper fashioned assemblage to produce the resultant cup-shaped section, and the joining stitches are passed through the said overlapped portions to give permanence to the finished bust section.

50 In order to increase the stretching qualities of the made-up bust section, the strips

composing the same may be longitudinally stretched during the time that they are stitched together so that, upon subsequent contraction of the joined strips to normal length due to their elastic qualities, the 60 through stitches are closed upon each other and are somewhat loosened in the fabric, whereby the fabric may be stretched in the direction of the length of the strips without being limited by the stitches and without 65 imposing undue tension upon the thread. When the stitches are applied to the overlapped strips in their normal or non-stretched condition, the bust sections composed of united strips may be stretched in 70 the direction of the length of the strips to a limited extent (which in some instances is sufficient for practical use) inasmuch as the stretching of the fabric serves to decrease the thickness thereof and to thereby effect a 75 loosening of the stitches to such extent as to permit elongation thereof.

In the drawings:—Figure 1 illustrates a brassière embodying my invention. Fig. 2 is a front elevation of one of the bust sections, with fragmentary portions of associated parts of the garment. Fig. 3 is a top plan view thereof. Fig. 4 illustrates the manner of closing a front opening brassière. Fig. 5 is an enlarged diagrammatic view of 80 two joined elastic strips illustrating the same when longitudinally stretched. Fig. 6 is a diagrammatic view of the parts shown in Fig. 5 when the elastic strips assume their 85 normal length.

As shown in the drawings, 10, 10 designate the bust sections, 11 the back or connecting band, and 12, 12 the shoulder straps of a brassière of a generally known type. As herein shown, the brassière is adapted to be 95 opened in front, but the invention is adaptable to garments which open in the back.

Each of the bust sections is composed of a plurality of horizontally arranged elastic strips 14, which are assembled in overlapping relation at their marginal portions, and are joined by lines of stitching 15 sewed through said overlapping portions. In the present instance, the strips are of uniform width such as may be cut from an elastic 100 web. The said strips are stitched at their inner ends to the back or body band 11 and at their outer ends to binding braids 16 which constitute the free margins of the bust sections, said braids carrying the fastening 110

devices, as hooks and eyes herein shown, when the brassière is opened in the front.

- In assembling the strips to produce the bust section, when so made of uniform width, the bust section is fashioned to produce the desired cup-like contour by variably overlapping the strips at their marginal portions from end to end of the strips, as will clearly appear from an inspection 5 of Fig. 2. As shown in the said figure the overlapping of the strips increases from the intermediate portions thereof toward each end, the marginal overlapping of the strips being greatest at the inner or rear 10 edges of the bust sections. The particular extent of the marginal overlap between adjoining strips, from end to end thereof, varies according to the particular contour of the bust section desired.
- 15 In order to increase the capacity of the bust sections to stretch in a direction lengthwise of the strips, the elastic strips may be stretched while being stitched together. Thus Fig. 5 may diagrammatically illustrate 20 the strips and stitches so stretched while being stitched together, while Fig. 6 may illustrate the strips and stitches after the strips have resumed their normal length under their own elasticity. It will be noted 25 in Fig. 6 that the stitches are closed toward each other so that they are not as taut as in Fig. 5 and that said stitches are, therefore, free to stretch or elongate with the stretching fabric to approximately the 30 length of the original stitches. If the strips be stitched together when unstretched, the reduction of thickness of the fabric due to stretching the same will allow for a limited 35 looseness and consequent stretching of the 40 stitches. In this event, Fig. 6 may be assumed to diagrammatically represent two joined strips in their unstretched condition, and Fig. 5 may likewise represent the strips after they have been stretched.
- 45 It is apparent that bust sections made in accordance with my invention may be produced much more economically than similar devices which are woven in one piece, inas-

much as commercial or staple stock may be employed in the construction of my improved garment while special machinery is required to produce the one-piece bust section. It is also apparent that bust sections made in accordance with my invention are 50 fully as elastic as prior one-piece bust sections and may be as accurately made to a 55 desired contour.

I claim as my invention:—

1. A brassière having an elastic cup-shaped bust section composed of a plurality 60 of elastic strips overlapped at their margins throughout their length and joined throughout the length of their overlapped parts by stitches which extend through said overlapped portions.

2. A brassière having an elastic cup-shaped bust section composed of a plurality 65 of elastic strips joined at their marginal portions by lines of stitches so disposed as to offer no restraint to the free stretching of 70 said elastic bust section in all directions.

3. A brassière comprising a back section and elastic bust sections, said bust sections each comprising a plurality of elastic strips overlapped at their margins and joined together at their overlapped portions by lines 75 of stitches arranged to permit free stretching of the section in the direction of the length of the said strips.

4. A brassière having an elastic cup-shaped breast lobe supporting section composed of a plurality of flat elastic strips joined throughout their length by stitches which permit free stretching of the strips in the direction of their length, said strips 80 being fashioned relatively to each other to produce a cup-shaped lobe supporting section.

In testimony that I claim the foregoing as my invention I affix my signature in the 90 presence of two witnesses, this 5th day of June, A. D. 1914.

CLARENCE MAYER.
